CLAIM

The ornamental design for an automobile fog lamp
guard, as shown and described.

DESCRIPTION

FIG. 1 is a pictorial view of an automobile fog lamp
guard showing my new design.

FIG. 2 is a left side elevational view thereof.

FIG. 3 is a right side elevational view thereof.

FIG. 4 is a top plan view thereof.

FIG. 5 is a front elevational view thereof, the fog lamp
being shown in broken lines for illustrative purposes
only.

FIG. 1

FIG. 2

FIG. 5

FIG. 4

FIG. 3
